UNITED STATES PATENT OFFICE.

JOHN S. LENG, OF WEST NEW BRIGHTON, NEW YORK.

VALVE.

SPECIFICATION forming part of Letters Patent No. 298,865, dated May 20, 1884.

Application filed May 22, 1883. (No model.)

To all whom it may concern:

Be it known that I, JOHN S. LENG, of West New Brighton, in the county of Richmond and State of New York, have invented a certain 5 new and useful Improvement in Valves, of which the following is a specification.

My invention relates to what are commonly as "straight-way" or "gate" valves, in which the valve is opened and closed by a sliding 10 movement in a direction transverse to the "water way" or passage through the shell or casing, and in which the valve is in many cases attached to a carriage having a sliding movement in guides formed in the valve shell or 15 casing.

The invention consists in the combination, with a valve, its shell or casing, and means for moving the valve in a direction transverse to the water way or passage, the said valve being 20 preferably attached to a carriage movable in said direction, of an adjustable and removable seat screwed into one of the pipe sockets or openings of the shell or casing to a position inward of the outer end of said socket or opening, so as to leave on the outer side of the said 25 seat a screw-threaded portion of the socket or openings for the reception of a pipe. The valve-seat is faced off truly before being inserted in the shell or casing, and is then inserted into the pipe socket or opening and screwed in until it comes to an even bearing 30 on the valve, which previously has been moved into a closed position. In valves of the kind above referred to, the carriage to which the 35 valve is attached is often operated by an arm or cam-like lever mounted on a rock-shaft which projects from the valve shell or casing through a stuffing-box; and my invention also consists in a novel construction of this stuffing-box, as 40 particularly hereinafter described.

The invention also consists in a novel and simple means of connecting the valve with its carriage, as hereinafter described.

In the accompanying drawings, Figure 1 is a 45 sectional view of a valve embodying my invention. Fig. 2 is a section thereof in a plane transverse to the water way or passage through the valve. Fig. 3 is a plan, the bonnet of the shell or casing being removed and the valve 50 in an open position. Fig. 4 is a detail sectional view showing a portion of the rock-shaft and

stuffing-box, and Fig. 5 is a detail sectional view of the valve and carriage.

Similar letters of reference designate corresponding parts in all the figures.

A designates the shell or casing of the valve, which is of ordinary form, and is provided with the usual pipe sockets or openings, A'.

B designates the adjustable and removable valve-seat. It consists simply of a ring, the 60 inner face, a, of which is flat and forms the valve-seat proper. This ring is externally screw-threaded correspondingly to the pipe socket or opening A', and is capable of being screwed into said pipe-socket from the outer 65 end thereof to a position considerably inward of the outer end of the socket, so as to leave a screw-threaded portion of the socket on the outer side of the seat for the reception of a pipe. The pipe-socket is of course slightly 70 taper, and the seat is adapted to be screwed up tightly therein. The ring B, which forms the seat, is provided with two or more internal lugs or projections, b, with which a wrench 75 may be engaged to turn it in.

C designates the valve proper, which is attached to and moved in a direction transverse to the water way or passage by a carriage, D, which is capable of sliding freely in guides c, formed in opposite sides of the shell or casing 80 A. These guides are inclined relatively to the valve-seat B, so that the valve will be crowded against the seat as the carriage is moved downward or inward. The guides c are open at the upper ends, and the casing or shell 85 is provided with the ordinary screwed cap or bonnet A². When this cap or bonnet is removed, the carriage may be inserted directly into the guides.

The valve C is connected with the carriage 90 D in a novel manner, as seen most clearly in Fig. 5. The back of the valve is rounded or convex, and at the center thereof there is a projection, d, which enters a hole, e, in the carriage D, and is secured therein by a washer, f, and a screw, g, which is inserted into the said projection. The projection d is somewhat smaller in diameter than the hole e, which it enters, and the carriage is beveled on each side around the hole e, so that it can adjust itself with perfect freedom in any direction independently of the carriage, although it moves

with the carriage in a direction transverse to the water way or passage. As seen in Fig. 5, the washer *f* is of such small diameter that it will enter the beveled opening on the back of 5 the carriage around the hole *e*.

In inserting the seat *B* the valve is moved down into its closed position, and the seat, the face *a* of which has been previously surfaced off truly, is screwed in until it comes to a solid 10 bearing on the face of the valve. In the present example of my invention the carriage *D* is moved to open and close the valve *C* by means of a rock-shaft, *E*, which projects outside the shell or casing *A*, and a cam-like lever or 15 arm *F*, fitted upon the shaft within the shell or casing. The rock-shaft *E* may be turned by means of a lever or arm, *E'*, secured to it, and within the shell or casing it has a square or angular portion, *h*, to which the 20 cam-like lever or arm is fitted. The carriage *D* is provided on the back with pairs of arms *i* *i'*, between which said pairs the lever *F* works, and the lever has horns *j*, projecting in opposite directions and between the two arms 25 of each pair. When the rock-shaft *E* is turned in one direction, the horns *j*, acting on the arms *i*, raise the carriage and open the valve, and when turned in the other direction said horns engage with the arms *i'* and move the 30 carriage to close the valve. In moving the carriage to close the valve the portion or projection *k* on the lever bears on top of the carriage, as shown in Fig. 1, between the arms *i* *i'*, and thus presses the carriage down and 35 wedges the valve up against its seat.

Upon the side of the shell or casing *A* is a recessed projection or hub, *A*³, like an ordinary stuffing-box, and which receives a collar, *E*², on the rock-shaft.

40 *G* designates an externally screw-threaded plug or gland, which screws into the projection *A*³, like the gland of a stuffing-box.

In the outer face of the collar *E*² is formed 45 an annular groove, *l*, and the plug or gland *G* is formed with a valve-like projection or face, *m*, which, as the nut is screwed up, enters and snugly fits in the groove *l*. The groove forms a seat, and the plug or gland, or the projection thereon, forms a valve, which prevents leakage around the rock-shaft and 50 between it and the plug or gland. The collar *E*² fits and is held between the rigid surfaces formed by the bottom of the stuffing-box and the end of the plug or gland.

55 If desired, the projection *m* might be on the collar *E*² and the groove *l* in the end of the nut.

What I claim as my invention, and desire to secure by Letters Patent, is—

60 1. The combination, with a valve, its shell or casing, and means for moving the valve in a direction transverse to the water way or

passage, of an adjustable and removable seat 65 screwed into one of the pipe sockets or openings of the shell or casing to a position inward of the outer end of the socket or opening, so as to leave on the outer side of said seat a screw-threaded portion of the socket or opening, for the reception of a pipe, substantially as herein described. 70

2. The combination of a valve shell or casing, a carriage sliding therein in a direction transverse to the water way or passage, a valve attached to the carriage, but capable of adjusting itself in all directions independently 75 of the carriage, and an adjustable and removable valve-seat screwed into one of the pipe sockets or openings in the shell or casing to a position inward of the outer end of said socket or opening, so as to leave on the outer side of 80 said seat a screw-threaded portion of the socket or opening, for the reception of a pipe, substantially as herein described.

3. The combination, with the stuffing-box, 85 of the valve-operating rock-shaft provided with a collar fitting in said box, and the outer side of which forms a valve-seat, and an externally screw-threaded plug or gland screwed into the box, and having a valve-like face which bears upon and forms a tight joint with 90 said collar to prevent leakage between the shaft and the plug or gland, the said collar being held between the rigid surfaces formed by the bottom of the stuffing-box and the inner end of said plug or gland, substantially as 95 herein described.

4. The combination of the stuffing-box *A*³, the shaft *E*, provided with a collar, *E*², in the outer side of which is a grooved seat, *l*, and the externally-screw-threaded plug or gland *G*, having a valve-like projection, *m*, which enters and forms a tight joint with said groove, the said collar being held by the rigid surfaces formed by the bottom of the stuffing-box and the inner end of said plug or gland, substantially 105 as herein described.

5. The combination of the valve *C*, having a rounded back and a projection, *d*, the carriage *D*, having the hole *e* beveled in the back, and the washer *f* and screw *g*, substantially 110 as herein described.

6. The combination of the valve *C*, carriage *D*, provided with the arms *i*, the lever *F*, fitting between said arms, and provided with horns *j*, projecting from opposite sides, and engaging with the arms *i* *i'*, and also provided with the portion *k*, bearing on the top of the carriage at a point between the arms *i* *i'* and the rock-shaft *E*, substantially as herein described. 115
